UNITED STATES PATENT OFFICE.

FRANK C. ROBERTS, OF PHILADELPHIA, PENNSYLVANIA.

FIREPROOF SHUTTER.

SPECIFICATION forming part of Letters Patent No. 782,468, dated February 14, 1905.

Application filed March 18, 1904. Serial No. 198,753.

To all whom it may concern:

Be it known that I, FRANK C. ROBERTS, a citizen of the United States, residing at Philadelphia, in the county of Philadelphia and State 5 of Pennsylvania, have invented or discovered new and useful Improvements in Fireproof Shutters, of which the following is a specification.

My invention relates to fireproof shutters 10 or shutters which may be closed by the action of a fluid, and, if desired, the shutters while closed may be sprayed with water or other liquid.

It is the object of my invention to provide 15 fireproof shutters composed of metal which may be released by the action of a fluid-operated mechanism which normally holds the shutters raised, but which upon release permits or causes the shutters to drop in front of 20 the windows, the fluid being sprayed upon the outside of the shutters as soon as the latter have been released.

The shutters may be applied to any number 25 of windows, and the operating mechanism therefor may all be connected to a system of pipes which will carry the operating and spraying fluid to the shutter-operating mechanism. The fluid will be admitted to the pipes by one 30 or more valves conveniently located in the building where the shutters are used, so that upon the actuation of any valve the shutters may be closed and sprayed. The piping system may be divided into sections, so that a certain number of shutters may be operated 35 from one set of pipes and another set of shutters from another set of pipes, the sets of pipes being controlled by separate valves. The piping and valves may be arranged so that by the actuation of one or more valves one or 40 more shutters may be closed and sprayed.

Referring to the drawings, Figure 1 is a front elevation showing one form of my invention, the shutter being shown raised. Fig. 2 is a vertical section taken on the line 2 2 of 45 Fig. 1, showing the shutter in the raised position. Fig. 3 is a similar section showing the shutter in its lowered position. Fig. 4 is a front elevation of a second form of shutter-releasing mechanism, differing somewhat from 50 that shown in Figs. 1, 2, and 3. Fig. 5 is a

vertical section taken on the line 5 5 of Fig. 4. Fig. 6 is a third form of my shutter-releasing mechanism, and Fig. 7 is a vertical section taken on the line 7 7 of Fig. 6. Fig. 8 is a front elevation of a fourth form of my invention, and Fig. 9 is a vertical section taken on the line 9 9 of Fig. 8. Fig. 10 is a front elevation of a fifth form of my invention, showing only a fragment of the shutter; and Fig. 11 is a vertical section taken on the line 11 11 of Fig. 10. Fig. 12 is a plan view, partly in section, taken on the line 12 12 of Fig. 1. Fig. 13 is a fragmentary view showing in plan view one end of the folded shutters shown in Figs. 2 and 9, together with a horizontal section of 60 one of the guideways which guides the shutters as they are raised and lowered and holds them in place. Fig. 14 is an end view of the shutters shown in Figs. 2, 9, and 13, the shutter being shown raised or folded. Fig. 15 is a fragmentary view showing the shutters illustrated in Fig. 14 in an extended or lowered position. Fig. 16 is a front elevation of a 65 sixth form of my invention. Fig. 17 is a vertical section on the line 17 17 of Fig. 16. Fig. 18 is a vertical section taken on the line 18 18 of Fig. 19. Fig. 19 is a vertical section on the line 19 19 of Fig. 18. Fig. 20 is a vertical section on the line 20 20 of Fig. 21, showing a seventh form of my invention. Fig. 21 is a 70 front elevation of Fig. 20. Fig. 22 is a detail showing the manner of connecting the sections of the shutter shown in Fig. 20.

Referring now to the form of my invention shown in Figs. 1, 2, and 3, 1 designates 75 a window provided with a shutter 2. The shutters are shown in Figs. 1 and 2 in a folded position at the top of the opening in the wall 3, in which the window is located. The shutter is supported on the rest or arm 4, pivoted 80 at 5 to the hangers 6. (See Fig. 12.) At the top of the window-opening the casing 7 is provided with the vertical opening 8, in which reciprocates the piston 9. To the bottom of the piston is attached a piston-rod 10, whose 85 lower end carries a pair of links 11. The lower end of these links is connected to the middle of the toggle-levers 12 and 13, the former being connected to the arm 14 of the casing 7 and the latter to the detent or catch 90 100

15, pivoted to the casing 7 at 16 and provided with a hook or shoulder 17. The hook 17 is arranged to support the lug 18 on the front end of the rest 4 when the rest is in its horizontal position, as shown in Figs. 1 and 2, where the latter is shown supporting the folded or raised shutter. The upper end of the opening 8 in the casing 7 is connected to the pipe 19, leading from the distributing-pipe 20, 10 which may supply fluid for any number of windows, since any number of shutter-releasing mechanisms may be connected thereto. 21 represents horizontal pipes arranged at the upper portion of the window-opening and provided with a number of spraying-openings 22 on the side thereof toward the window. The inner ends of the pipes 21 are secured in the casing 7 and communicate laterally with the opening 8 therein. The pipes 21 have 15 their outer ends closed by the caps 23.

The shutter illustrated in Figs. 1, 2, and 3 is shown in detail in Figs. 12, 13, 14, and 15. This shutter is composed of sections 24, whose length is approximately the width of the window-opening. Each section 24 has riveted to its under side the strap 25, which preferably extends from end to end thereof and has lateral extensions or pivots 26, provided with antifriction-rollers 27, which are seated in the 20 vertical guideway 28 at the sides of the window-opening. The inner corners of the sections 24 have riveted to their under sides lateral lugs or pivots 29. The pivot 26 at each end of each section is connected to the pivot 29 of the corresponding end of the next section below by means of the link 30. The upper section 24 extends only to the front, since a rear portion would engage with the upper part of the window-opening and prevent the 25 pivotal movement of this section. The top section may have a rearward extension, provided its pivotal point is located sufficiently far from the top of the window-opening. The pivot 26 of the top section preferably forms the fixed support for the shutter. When the sections are folded, as in Fig. 14, they occupy but a small portion of the window-opening and interfere in no manner with the operation of the windows. The sections 24 will have such 30 a width that when the shutter is lowered or suspended, as shown in Fig. 15, the top edge of the one section will be overlapped by the lower edge of the next section above. There should be a sufficient number of these sections to reach to the bottom of the window-opening when they have been released. The guideway 28 extends from the top of the window-opening to the bottom thereof and serves to guide and hold the shutter in its place in 35 front of the window.

The operation is as follows: Normally the shutters will be folded and supported by the rest 4, as shown in Figs. 1 and 2, the rest being held in a vertical position by means of the 40 detent or catch 15 interlocking with the lug

18 on the rest. Normally the toggle-levers 12 and 13 will lie in a straight line, as shown in Fig. 1, and the piston will be at its upper position, as shown in Fig. 2. When water under pressure is admitted to the pipe 20, the piston 9 is forced down, causing the toggle-levers to become bent. The bending of the toggle-levers withdraws the catch 15 from the lug 18, whereupon the rest 4 swings on its pivot 5 into the position shown in Fig. 3. 75 The shutter being now unsupported unfolds or drops, so as to assume the position shown in Figs. 3 and 15, the antifriction-rollers 27 traveling down the guides 28. As the piston 9 moves from its upper to its lower position it uncovers the ports from the opening 8 into the spraying-pipes 21, whereupon the water will be sprayed upon the outside of the shutter to keep it cool, whereupon the shutter will not become so hot as to be warped out of 80 position or to set on fire the woodwork of the window-casing or other material near the window. It will be noticed that the piston 9 is at the same time a valve for opening and closing the ports of the spraying-pipes and a motor for operating the detent or catch for releasing the shutter.

Referring now to Figs. 4 and 5, I show a form of shutter 2' different from that shown in the preceding figures. The shutter shown in Fig. 5 consists of a number of sections 24', the edge of one section being hinged to one edge of the next lower section, as shown, the section being hinged and operated in a manner very similar to the folds of a bellows. The middle of the 95 sections is provided with antifriction-rollers 27', which lie in the guideway 28. I provide a casing 7', in which is pivotally supported the blade or arm 9', capable of oscillating on the axis 31, having the extensions 32 external to 100 each end of the casing. Secured to each of the extensions 32 is a detent or catch 15', provided with a hook or shoulder 17', which supports the outer end of the rest 4', pivoted at 105 5 to the hangers 6, only one being shown. 110 The inner ends of the spraying-pipes 21 are secured to the outer ends of the water-passage 33, lying below the casing 7' and communicating with the interior thereof by means of the port 34. The supply-pipe 19 is secured 115 to the upper part of the casing and communicates with the interior thereof. The blade 9' normally covers the port 34; but when water is admitted through the pipe 19 it pushes the blade downward away from the port and at 120 the same time oscillates the axis 31, the extensions 32, and the detents 15', so that the latter are removed from beneath the rest 4', whereupon the shutter 2' is released in an obvious manner. The shutter immediately falls 125 in front of the window and the water is sprayed upon the same from the pipes 21 and the passage 33.

Referring now to Figs. 6 and 7, the parts are very similar to those of Figs. 4 and 5. 130

In Figs. 6 and 7 the rest for the shutter consists of a pair of levers 4², supported between their ends on the shaft 5², carried by the hangers 6², depending from the casing. The ends 5 of the bottom section of the shutter 2² being supported by the inner ends of the rest 4², the outer ends of the levers are in engagement with the lower ends of the detents or catches 15². These catches are operated in exactly 10 the same manner as the catches of Figs. 4 and 5. When water is admitted to the pipe 19, the blade 9' is forced to the left, thereby causing the port 34 to be uncovered and the detents 15² to be removed from above the outer 15 ends of the rest 4². The result is that the shutter at once falls in front of the window, and the water is sprayed upon the shutter, as in the other forms of my invention.

Referring to Figs. 8 and 9, I provide the 20 rest 4³, pivoted between the hangers 6³, depending from the bracket 35. One end of the rest supports the shutter 2, while the other is held in position by the detent 15³, having the hook 17³ engaging with the lug 18³ on the 25 rest 4³. This detent is pivoted to the bracket 35 and is connected by link 11³ to the piston-rod 10³, to which the piston 9³ is attached. The water entering through the pipe 19 operates the piston-rod and the link in the same 30 manner as in Figs. 1, 2, and 3. The movement of the piston to the right removes the detent from over the lug 18³ and admits water to the passage 33 and the pipes 21 in the same manner as in Figs. 1, 2, and 3.

Referring now to Figs. 10 and 11, the shutter 35 has the same form as shown in Figs. 5 and 7 and the vertical piston and piston-rod, as shown in Figs. 1, 2, and 3. The casing 7 is provided with a bracket or hanger 6⁴, to which is pivoted the lever or arm 36. The lower edge of 40 the bottom slat of the shutter is provided with the rod 37', which extends out beyond the sides of the shutter, as shown in Fig. 10, where the one of the outer ends of the rod 37' 45 is shown resting on the support or bracket 37, secured to the side of the window-opening. The free end of the arm 36 is beveled, so that its upper edge is longer than its lower edge and overhangs slightly the lower section of 50 the shutter. The piston-rod 10⁴ has its lower end resting upon the arm 36. The opening 8 in the casing communicates with the passage or port 34', which leads to the spraying-pipes 21. When water is admitted to the pipe 55 19, the piston 9⁴ will be pushed down, causing the arm 36 to be swung downwardly. As the free end of the arm is beveled, as described, it will force the shutter off the support 37, whereupon the shutter will fall in front of the 60 window. At the same time water will be admitted to the spraying-pipes and the shutter will be cooled, as in the other forms of my invention.

Referring now to Figs. 16 to 19, the win-

dow 1 may be covered by the shutter-sections 65 24², supported on the inclined tracks 38, having their inner ends lowest and meeting above the middle of the window. The shutter-sections are suspended on antifriction rollers or 70 wheels 39 and are held laterally away from the window by means of cords or cables 40, each of which passes over a sheave 41, located beyond the outer wheel 39 of each section. One end of each cable or cord is secured to a shutter-section, and the other end is secured to the 75 winding-drum 42, located above the window. The drum is provided with a ratchet-wheel 43, normally held from rotation in a direction to release the shutter-sections by the pawl or dog 44, oscillatory on the pivot or pin 45. The 80 end of the dog opposite that which engages the ratchet-wheel 43 is connected by the pair of links 46 to the lower end of the piston-rod 10⁵ of the piston 9⁵, slidable in the casing 7. The pipe 19 leads into the opening 8 in the 85 casing 7 above the piston 9⁵. The port or passage 34' leads from the opening 8 to the pipe 47, whose lower end leads to the sprinkler-pipes 21. When water is admitted to the pipe 19, it pushes the piston 9⁵ downwardly. This 90 action of the piston causes the pawl 44 to release the ratchet-wheel 43, whereupon the shutter-section 2² will run down the tracks 38, so as to cover the window. The piston 9⁵ in this action passes below the port 34² and permits 95 the water to enter the spraying-pipes 21 and to be sprayed upon the shutter, as shown in Fig. 17.

Referring now to Figs. 20 and 21, the pipe 19, the casing 7', the axis 31, the blade 9', the 100 extensions 32, the catches or arms 15², the port 34, the passage 33, the hangers 6², and the rest 4² are substantially as shown on Figs. 6 and 7. The rest 4², however, in Fig. 20 supports the weight 48, to which the lower 105 end of the shutter 2² is attached. The shutter is composed of a series of sections or slats 24², secured together at their edges by hinges, as shown in detail in Fig. 22. The shutter is normally wound up on the roller 49. The 110 catch 15² has an arm 50, which lies in the path of and above the weight 48 and serves to push downward on the weight 48 in case the shutter sticks after being released by the rest 4². (Shown on Fig. 20.) The weight 48 is guided 115 in guideways 51 (only one being shown) at the sides of the window-opening. The roller 49 is located above the window, and the shutter travels down through the slot 52 in the top 120 of the window-opening.

In Figs. 4, 7, and 20 I show the casing 7', provided on its under side with a port 53, which leads from the interior thereof to the outside to drain the same.

Referring to Figs. 2, 3, 11, 12, and 19, and 125 particularly to Fig. 12, it will be noted that the piston or valve-stem is cross-shaped, while the passage in which it reciprocates is round,

whereby the water may be drained from the casings through the angular spaces between the casings and the said stems.

On Fig. 3 I show in dotted lines a cord 53, 5 which passes over the sheave 54 at the top of the window-opening and has one end attached to the bottom of the shutter. By pulling on the cord the shutter may be hoisted to its raised position. This cord and sheave may 10 be applied in all cases where the folding shutter is used.

All the shutters will preferably be iron, but they may be of other material, and the fluid used will preferably be water; but I do not 15 wish to be limited thereto.

Although I have described the several parts of my invention in considerable detail, I would have it understood that I do not limit myself to the specific details shown, as many changes 20 may be made while still retaining the spirit thereof.

My shutters may be used to cover doors and other openings.

Some of my claims are not limited to any 25 definite means for releasing or causing the shutter to close, and in these claims I do not intend to be limited to fluid-operated means, as other means—such as electricity, steam, air, &c.—may be used.

30 It would be possible to have the blade 9' close a switch which controls an electric motor driving the drum or roller 49. The detent-arms shown would be modified to carry the movable member of the usual switch.

Having described my invention, I claim— 35

1. A shutter, means for holding the same withdrawn, a fluid-operated means for releasing said shutter, and means made operative by said fluid-operated means for directing a cooling fluid upon the shutter. 40

2. A shutter, means for holding the same withdrawn, a fluid-operated means for releasing said shutter, and means made operative by said fluid-operated means for directing upon the shutter the same fluid that operates 45 the said fluid-operated means.

3. A shutter, means for holding the same withdrawn, a spraying-pipe for directing a cooling fluid on said shutter, and a valve-motor operable first for releasing said holding 50 means and afterward for permitting said fluid to pass into said spraying-pipe.

4. A shutter, a rest for supporting the same, a catch for holding the rest in a position to support the shutter and a fluid-operated means 55 for removing the catch from said holding position.

5. A shutter, means for holding the same withdrawn, a fluid-operated means for releasing the said shutter, and means for directing 60 a cooling fluid upon the shutter, after its support has been released.

Signed at Philadelphia this 15th day of March, 1904.

FRANK C. ROBERTS.
